184,128

LAUNDRY DROP BOX

Tate J. Hall, Santa Fe, N. Mex.

Application January 24, 1958, Serial No. 49,387

Term of patent 14 years

(Cl. D58—4)

Fig. 1

Fig. 3

Fig. 2

Figure 1 is a front perspective view of a laundry drop box showing my new design;

Figure 2 is a rear perspective view thereof; and

Figure 3 is a top plan view thereof.

I claim:

The ornamental design for a laundry drop box, as shown.

References Cited in the file of this patent

UNITED STATES PATENTS

D. 107,658	Petzke	Dec. 28, 1937
D. 142,752	Tyler	Oct. 30, 1945
2,108,464	Antonsen	Feb. 15, 1938
2,602,584	Croft	July 8, 1952

OTHER REFERENCES

American Bicyclist and Motorecyclist, August 1957, page 72, left side, below center of page.